UNITED STATES PATENT OFFICE.

JOHN E. BAILEY, OF MILWAUKEE, WISCONSIN.

COMBINATION DRAFTING IMPLEMENT.

1,139,746.

Specification of Letters Patent. Patented May 18, 1915.

Application filed December 12, 1912. Serial No. 736,373.

To all whom it may concern:

Be it known that I, JOHN E. BAILEY, a subject of the King of Great Britain, residing at Milwaukee, in the county of Milwaukee and State of Wisconsin, have invented new and useful Improvements in Combination Drafting Implements, of which the following is a specification.

This invention relates to drafting applications and more particularly to a combination T-square and protractor and a means for mounting the same upon a drawing board.

The primary object of this invention is to provide a convenient and novel means whereby a draftsman may compute the degree of an angle with great rapidity, accuracy and convenience.

Another object of this invention is to combine a protractor and a T-square by mounting the protractor upon the T-square, and to provide a straight edge in connection with the protractor so that the draftman may accurately, as well as, easily, lay off any desired angle upon his paper.

Another object is to slidably mount this combined T-square and protractor upon the board so that at all times, the greatest accuracy may be obtained in the drawing, besides always having the tools in close proximity to the draftsman and in a convenient place.

Among many other objects of the device are: to provide one of the members upon which the T-square is slidably mounted with graduations so that in cases where absolute accuracy is not necessary, the use of an extra scale may be abandoned; the provision of novel and efficient caps or thumb nuts upon the various studs used in the device, which will, when the threads become slightly worn still cause a firm and true connection between the cap and the stud; and also to provide a novel and efficient means for mounting the head of a T-square upon the blade portion in a manner to prevent all possibility of splitting either the head or the blade by the screws used in securing the tool.

With the foregoing and other objects in view, this invention consists essentially in the provision of a specially constructed T-square having a protractor slidably mounted thereon, a straight edge connected to the protractor indicator and both the straight

edge and the indicator pivotally mounted upon the protractor, a specially constructed board having a T-square slidably mounted thereon and graduations upon one of the members upon which the T-square is mounted.

In describing the invention in detail, reference will be had to the accompanying drawings wherein like characters designate like or corresponding parts throughout the several views and in which:

Figure 1 is a top plan view of the entire device, showing some parts broken away. Fig. 2 is a sectional view on the line 2—2 of Fig. 1. Fig. 3 is a sectional view on the line 3—3 of Fig. 1, showing the cap removed. Fig. 4 is a sectional view on the line 4—4 of Fig. 1, and Fig. 5 is a detail view of the manner of mounting one end of the T-square on the supporting member of the brackets for holding the square.

In the drawings, 1 denotes the blade of the T-square which has its edge 2 beveled as is clearly shown at 3. The other edge 4 is beveled a short distance inwardly as at 5 from where the projection 6 extends outwardly. The projection 6 has a straight edge 7. The end 8 of the T-square blade 1 is provided with a cut-out portion 9 in which is seated the head 10 of the T-square. In this instance, the head is an angled member having the part 11 bent downwardly and at right angles to the part 12. The head 10 is securely held in the cut-out portion 9 by means of a plurality of screws 13, which have beveled heads 14. The beveled heads 14 of the screws 13 are countersunk into the end of the blade 1. A metallic plate 16, having a facial projection 17 upon its outer edge, is seated in a recess 18 in the blade 1 and the screw head 14 is seated in an opening in the plate 16. Mounting this small metallic plate 16 in the T-square blade 1 prevents the blade from splitting when the screws 13 are inserted therein. The angled end 11 of the T-square head 10 is provided with an opening or hole 19 for the reception of the screw-threaded stud 20. The stud 20 has a head portion 21 upon one end and this head 21 is slidably mounted in an opening in the square member 22. The member 22 is connected by any suitable means (not shown) to the edge 23 of the drawing board 24. The angled portion 11 of the T-square head 10 slidably engages the outer side of

100

110

the member 22 and is held in engagement therewith by the spring 25 which is secured at its ends 27 and 28 to the T-square head 10 by means of screws 29 or any other suitable fastening means. The spring 25 is bent, as is clearly shown in Fig. 1 of the drawings, and the center portion 30 which is provided with an opening 31 for the reception of the stud 20, and engages a cap or thumb nut 32. This nut 32 being in threaded connection with the stud 20 is a means for securely holding the T-square in any desired position along the board.

The other end 33 of the T-square blade 1 is provided with an opening 34 for the reception of a stud 35. The stud 35 has a cylindrically shaped head 36 which is provided with a longitudinally extending opening 37 centrally located therein. A thumb nut or cap 38 is screwed upon the stud 35 and has an annular ring 39 which is stud 35 and has an annular ring 39 which is provided with corrugations, disposed near the inner end thereof. This annular ring 39 and the corrugations thereon provide a means for conveniently and securely gripping the cap 38 when it is desired to turn the same. A washer 40 is interposed between the cap 38 and the T-square blade 1. A spring 41 is seated in a recess 42 in the cap 38 and engages the inner wall 43 of the recess 42. This spring 41 tends to keep the washer 40 in contact with the T-square blade 1 and also when the threads get slightly worn on either the cap 38 or the stud 30 to keep a firm and secure connection between the two.

A hollow cylindrical member 43, provided with two openings 44 disposed directly opposite each other, forms a covering or cap for the head 36 of the stud 34. A tubular member 45 is mounted in brackets 46, which brackets 46 are secured to the edge 47 of the board 24. The brackets 46 are provided with elongated slots or openings 48 for the reception of the tubular member 45. A plug 49 is mounted in each end of the tubular member 45 and a cap or thumb nut 49', identical in construction with the cap 38 is screwed on the end thereof. The tubular member 45 is further provided with graduations so that in cases where extreme accuracy is not necessary, the use of a scale may be dispensed with. The member 22 is also provided with graduations and when it is desired one of the members 22 or 45 may be provided with graduations of the metric system while the other has the graduations of the English system of linear measurement thereon. Or these two members may be graduated according to the discretion of either the manufacturer or the purchaser. While both of the members 22 and 45 are here shown provided with graduations, it is to be under-

stood that the graduations may be eliminated from either or both of them without departing from the spirit of the invention.

A protractor 50 is slidably mounted on the T-square blade 1 and has its dial 51 graduated as shown at 53'. The under surface of the protractor dial 51 is provided with an extension 52 which is shaped so as to conform with the beveled edge 5 of the T-square blade 1 and to form a slidable connection between the protractor 50 and the T-square blade 1. The outer side 53 of the protractor dial 51 is bent downwardly at right angles to the main portion of the same and a plug 55 having one edge beveled 50 so as to conform with the angled edge 3 of the T-square blade 1 is mounted thereon. The plug 55 is provided with an opening 56 for the reception of a stud 57 which has a cap or thumb nut 58 in threaded engagement to the outer end of the same.

A cap 58 is provided with a recess 59 in which a spring 60 is disposed. A washer 61 is interposed between the cap 58 and the protractor dial 51.

An indicator or pointer 62 is pivotally mounted upon the dial 51 by means of the stud 63. This stud 63 extends through the protractor dial 51 and has its head 64 seated in a counterbore in the straight-edge 65. A washer 66 is interposed between the straight-edge 65 and the protractor dial 51. The indicator 62 and the straight-edge 65 are both rigidly connected to the studs 62 so that when one is moved, the other will 100 move correspondingly.

A cap 67 which is provided with a recess 68 for its reception of a spring 69 is secured upon the threaded end of the stud 63 and holds the several parts of the protractor, namely the indicator 62, the dial 54, the washer 66 and the straight-edge 65 in engagement with each other. The cap 67, as are the caps 38, 59, and 32, is provided with an annular projection 70, which annular projection 70 is provided with corrugations on its outer edge. This projection 70 and the corrugations thereon greatly aid in gripping the cap when it is desired to turn the same. A washer 71 is interposed 110 between the cap 67 and indicator 62.

A small knob 72 is secured to the outer end 73 of the straight-edge 65 and assists in manipulating the straight-edge 65.

It is thought from the foregoing description and the drawings, the advantages and novel features of this invention will be readily comprehended.

In practical fields, certain minor features of construction, combination and arrangement of parts, may necessitate alterations to which the patentee is entitled provided such alterations are comprehended within the scope of what is claimed.

Having fully described the invention,

what is claimed as new, useful and novel is:—

1. In a drafting implement, a board, guide members extending along two opposite sides of said board, a T-square slidably mounted on said guide members, a flat spring mounted upon the head of said T-square, a stud, said stud being slidably engaged with one of said guide members and passing through said spring, and a nut for engagement with said stud for tensioning said spring.

2. In a drafting implement, a board, guide members extending along two opposite sides of said board, a T-square slidably mounted on said guide members, a spring mounted upon the head of said T-square, said spring having an opening formed therein, one of said guide members having a slot formed therein, a stud slidably arranged in said slot, said stud extending through the opening in said spring, and a thumb nut threaded on said stud for regulating the tension of said spring.

3. In a drafting implement, a board 25 structure, having guide members extending along two opposite sides thereof, a straight edge slidably guided by said guide members, and means for holding one end of said straight edge in adjusted position on one of said guides comprising, a thumb nut, a shaft having a shank and an enlarged head which encompasses said guide, said shank extending through said straight edge and adjustably seated in said thumb nut, a 30 washer interposed between said thumb nut and said straight edge and, a spring seated in a recess in said thumb nut about said shank and engaging said washer for forming a firm connection between the washer 40 and the straight edge and means for holding the other end of the straight edge in engagement with the other of said guides.
